UNITED STATES PATENT OFFICE

151,598

DESIGN FOR AN ADJUSTABLE BRASSIÈRE

Julius Cohn, New York, N. Y.

Application November 25, 1947, Serial No. 142,796

Term of patent 7 years

(Cl. D20—4)

To all whom it may concern:

Be it known that I, Julius Cohn, a citizen of the United States of America, residing in New York, county of New York, and State of New York, have invented a new, original, and ornamental Design for an Adjustable Brassière, of which the following is a specification, reference being had to the accompanying drawing, forming part thereof.

Fig. 1 is a front view of an adjustable brassière, showing my new design.

Fig. 2 is a rear view thereof.

Fig. 3 is a fragmentary view as shown in Fig. 1, illustrating the strap portion in open position.

I claim:

The ornamental design for an adjustable brassière, substantially as shown and described.

JULIUS COHN.
